HORN TYPE LOUD-SPEAKER

Lloyd J. Bobb, Philadelphia, Pa., assignor to
 Philco Radio and Television Corporation,
 Philadelphia, Pa., a corporation of Delaware

Application March 11, 1939, Serial No. 261,357
 In Great Britain March 25, 1938

4 Claims. (Cl. 181—31)

This invention relates to a novel cabinet structure for a radio receiver and has for its principal object the provision of a cabinet structure wherein in a highly efficient horn coupling between the back of the loud-speaker diaphragm and the outside air is obtained by a novel arrangement of partitions or baffles which define successive chambers or passages whose respective volumes vary substantially exponentially, giving the effect of an exponential horn. The arrangement of the partitions or baffles is such that a minimum number of these elements are made to serve the desired purpose.

Another object of the invention is to provide a novel cabinet structure of this character wherein provision is made for accommodating parts of the radio receiver, such as the receiver chassis and batteries, in such manner that these parts reduce the volume of certain of the horn chambers or passages, thus causing such radio receiver parts to serve an additional purpose.

A further object of the invention is to provide a cabinet of novel construction wherein certain radio receiver parts are judiciously disposed and wherein the space which is not occupied by such parts is utilized for a novel baffle structure which, together with the cabinet walls, provides an effective horn as above mentioned.

Other objects and features of the invention will be apparent as the description proceeds. The invention may be clearly understood by reference to the specific embodiment shown in the accompanying drawing, wherein

Fig. 1 is a perspective view of a preferred form of the cabinet structure with certain parts broken away for the sake of illustration; and

Fig. 2 is a perspective view of one form of device employing the cabinet structure.

Referring first to Fig. 1, there is shown a box-like cabinet structure comprising a bottom 1, a top 2, side walls 3 and 4, and a back 5. The height and width of this structure are substantially equal and are about twice the depth. In other words, the height, width and depth are related substantially in the ratio 2:2:1. Extending between the side walls 3 and 4, there are provided two superposed horizontal partitions or baffles 6 and 7, the upper baffle 6 extending from the back of the cabinet forward about two-thirds of the depth of the cabinet, while the lower baffle 7 extends from the front of the cabinet backward about one-half the cabinet depth. The distances between the top 2 and upper baffle 6, between the two baffles 6 and 7,

and between baffle 7 and the bottom 1, are related substantially in the ratio 2½:3:10.

There are also provided two spaced L-shaped vertical baffles 8 and 9 having front portions extending between the baffle 7 and the top 2 and having rear portions extending between baffle 6 and the top 2. The distance between baffles 8 and 9 and the distances between these baffles and the side walls are substantially equal. A small vertical baffle 10 extends between the baffles 8 and 9 and between the baffles 6 and 7. The front central space *a* defined by the baffle 7, the top 2, the front portions of baffles 8 and 9, and the small baffle 10 is sufficiently large to serve as a chamber or receptacle for the loud-speaker 11, as illustrated. A front panel 12 extends between the side walls and between panel 7 and the top 2. This panel has an opening adjacent the speaker diaphragm.

In further accordance with the invention, the radio receiver proper, in the form of a unit 13 may be disposed on the bottom 1 centrally between the side walls 3 and 4 within the space defined by the bottom 1, the baffle 7 and the side walls 3 and 4. There are also provided batteries 14 and 15 which may be disposed in the rear corners at the bottom of the cabinet, as illustrated. These battery cases are preferably of the shape illustrated, each having an oblique wall 16, the purpose of which will be explained presently. Behind the radio receiver unit 13, there may be provided another battery 17.

In operation, the small space *a* in which the speaker diaphragm is disposed constitutes the throat of a horn for the sounds emanating from the rear side of the speaker diaphragm and, from this space, these sounds pass rearwardly through the somewhat larger space *b* defined by the top 2, the baffle 6, and the rear portions of baffles 8 and 9. From the space *b*, the sounds divide and pass divergently toward the side walls 3 and 4 between the top 2 and baffle 6, and then pass forwardly through the spaces *c* around the front edge of baffle 6 and then rearwardly through the spaces *d* between baffles 6 and 7. From the spaces *d*, the sounds again pass downwardly around the rear edge of baffle 7, and then forwardly through the larger spaces *e* between the baffle 7 and the bottom 1. The arrows indicate the directions of the sound waves. Thus, there are formed a plurality of successive spaces or chambers of increasing size or volume, such that a horn effect is obtained. It may now be noted that the receiver unit 13 and the batteries 14, 15

and 17 reduce the volume of the last space or chamber from which the sounds emanate and cause the effective volume of this space or chamber to be in proper relation to the other spaces or chambers formed by the baffles. The oblique surfaces 16 on the battery cases 14 and 15 assist in the provision of a horn mouth of increasing volume. These surfaces form a flaring sound-emitting mouth for the horn and also serve to 10 deflect the sounds.

In order to obtain maximum efficiency, the construction of the cabinet and the arrangement of baffles, as above described, should be rather critically adhered to, and the receiver unit 13 15 and the associated batteries should be so dimensioned that they reduce the volume of the sound-emitting space or horn mouth just sufficiently to provide the desired acoustic effect at the mouth of the horn structure. The cut-off frequency of 20 the cabinet structure will depend upon the dimensions employed in any instance. In order to vary the cut-off frequency, all of the dimensions should be varied in inverse proportion to the variation in cut-off frequency desired. For 25 example, assuming that a cabinet of given dimensions has a cut-off frequency of about 150 cycles per second, if it is desired to reduce the cut-off frequency by one-half, that is to 75 cycles per second, all linear dimensions, including 30 the diameter of the loud speaker, should be increased by a factor of two.

It will be apparent that the cabinet structure with the parts assembled therein, as shown in Fig. 1, forms a compact unit containing all of 35 the radio receiver parts and with the horn structure built into the casing or housing of the unit. This structure may itself form the cabinet of a radio receiver, in which case the front may be finished in any desired manner, such as shown 40 in Fig. 2, and be provided with an opening 18 adjacent the speaker, an opening 19 to accommodate the tuning dial, and openings 20 and 21 to emit sound from the mouth areas e. Obviously, the front may be of any suitable design 45 and appearance, that shown in Fig. 2 merely being illustrative of one possible form.

Alternately, the structure shown in Fig. 1 may be placed within a larger cabinet adjacent the front panel of such cabinet, the panel being provided with suitable openings. In such case, the 50 receiver unit and the batteries may or may not be disposed in the unit of Fig. 1. If these elements are not so disposed, the height of spaces e should be decreased so that the ratio of the heights of 55 spaces c, d, and e is substantially 2½:3:8. In the specific example given below, this is done by decreasing the height of space e two inches. Other methods of utilizing the structure of the 60 invention will be apparent to those skilled in the art.

Preferably, the baffles 6, 7, 8, 9 and 10 are assembled together to form a latticework structure or unit separate from the cabinet in order that this unit may be inserted bodily within the cabinet to provide the desired horn structure. Where the structure of Fig. 1 forms the radio cabinet and has a front panel closing the front thereof, the entire structure is preferably assembled as follows: The baffles are assembled to form a separate unit as above mentioned. The loud-speaker is inserted within the latticework and is mounted on the panel 10 thereof. The baffle structure is then inserted bodily from the rear of the cabinet, the back wall of the cabinet having been removed previously. The radio receiver parts are

also inserted in the cabinet from the back thereof, and finally the back wall is mounted in place.

In a specific example, the inside dimensions of the structure of Fig. 1 were as follows:

Bottom 1 and top 2 each were approximately 16 inches by 8½ inches.

Sides 3 and 4 each were approximately 16 inches by 8¾.

Back 5 was approximately 16 inches square.

Baffle 6 was approximately 16 inches by 5¾ inches.

Baffle 7 was approximately 16 inches by 4¾ inches.

The distance between baffle 6 and top 2 was approximately 2½ inches.

The distance between baffles 6 and 7 was approximately 3 inches.

The distance between baffle 7 and bottom 1 was approximately 10 inches.

Baffles 8 and 9 each were approximately 5½ inches deep at the top.

The distance between baffles 8 and 9, and the distance between these baffles and the side walls, was approximately 5¼ inches, allowing about ¼ inch for the thickness of the baffles.

The diameter of the loud-speaker diaphragm was approximately 4½ inches in diameter.

The magnet structure of the speaker was approximately 3½ inches in diameter and approximately 1⅓ inches deep.

This device had a cut-off frequency of about 180 cycles per second. The resonant frequency of the speaker diaphragm in air was about 175 cycles per second.

When the structure of the invention is employed, the loud-speaker may be modified by increasing the magnetic flux density in the air gap and decreasing the mass of the speaker cone. This increases the speaker efficiency at high frequencies with some loss in efficiency at low frequencies. However, this loss is balanced by the improved coupling between the air and the speaker cone brought about by the use of the cabinet structure, with the result that the overall efficiency of the entire acoustic unit is materially improved. Since the direct radiation at low frequencies from the front of the speaker is low, no trouble with interference patterns, due to phase differences in sound waves from the front and back of the loud-speaker, will obtain.

The structure provided by the invention also increases the power capabilities of the sound reproducing system. As is well known, in the conventional loud-speaker the power output is limited, due to the fact that the maximum possible excursion of the voice coil of the speaker is limited by the dimensions of the magnetic field, and the acoustic power is proportional to the square of this excursion. The present invention permits a much smaller movement of the voice coil for a given acoustic power output, and, therefore, the power capabilities of the sound reproducing system are materially increased.

Although a single form of the invention has been illustrated and described for the purpose of disclosure, it will be apparent that various modifications of the structure and various embodiments are possible without departing from the scope of the invention. For example, the structure may be embodied in a cabinet of the console type and may, if desired, form a part of such cabinet, in which case the receiver unit and the batteries may be positioned differently than shown.

I claim:

1. A sound reproducing apparatus, comprising a cabinet having front and rear panels, said front panel having at least two openings therein, a pair of vertically-spaced horizontal baffles within said cabinet, the lower one of said baffles extending from the front of said cabinet rearwardly and terminating in a rear edge spaced from the rear of the cabinet, the upper baffle extending from the rear of said cabinet toward the front of said cabinet and terminating in a front edge spaced from the front of the cabinet, a loud-speaker disposed above said lower baffle in front of said upper baffle adjacent one of said openings at the front of the cabinet for emitting sound from the speaker, a pair of vertical baffles arranged on opposite sides of said loud speaker to form a speaker compartment and extending rearwardly above said upper baffle to direct sounds rearwardly, and a panel extending between said vertical baffles and between said horizontal baffles, the said loud-speaker being characterized by having more efficient response at high frequencies than at low frequencies, and the said baffles being arranged to provide successive sound chambers of increasing cross-sectional area from the rear of the loud-speaker to the other opening in the front of the cabinet whereby to reproduce efficiently the low frequency sounds.

2. A sound reproducing apparatus, comprising a cabinet having front and rear panels, said front panel having at least two openings therein, a pair of vertically-spaced horizontal baffles within said cabinet, the lower one of said baffles extending from the front of said cabinet rearwardly and terminating in a rear edge spaced from the rear of the cabinet, the upper baffle extending from the rear of said cabinet toward the front of said cabinet and terminating in a front edge spaced from the front of the cabinet, a loud-speaker disposed above said lower baffle in front of said upper baffle adjacent one of said openings at the front of the cabinet for emitting sound from the speaker, a pair of vertical baffles arranged on opposite sides of said loud-speaker to form a speaker compartment and extending rearwardly above said upper baffle to direct sounds rearwardly, and a panel extending between said vertical baffles and between said horizontal baffles, the said loud-speaker being characterized by having more efficient response at high frequencies than at low frequencies, and the said baffles being arranged to provide successive sound chambers of increasing cross-sectional area from the rear of the loud-speaker to the other opening in the front of the cabinet whereby to reproduce efficiently the low frequency sounds, the last of the said successive sound chambers being of sufficient volume to accommodate one or more radio receiver components which reduce the volume of said chamber to cause its effective volume to be in proper relation to the preceding sound chambers.

3. A sound reproducing apparatus, comprising a cabinet having front and rear panels, said front panel having at least two openings therein, a pair of vertically-spaced horizontal baffles within said cabinet, the lower one of said baffles extending from the front of said cabinet rearwardly and terminating in a rear edge spaced from the rear of the cabinet, the upper baffle extending from the rear of said cabinet toward the front of said cabinet and terminating in a front edge spaced from the front of the cabinet, a loud-speaker disposed above said lower baffle in front of said upper baffle adjacent one of said openings at the front of the cabinet for emitting sound from the speaker, a pair of vertical baffles arranged on opposite sides of said loud-speaker to form a speaker compartment and extending rearwardly above said upper baffle to direct sounds rearwardly, and a panel extending between said vertical baffles and between said horizontal baffles, the said loud-speaker being characterized by having more efficient response at high frequencies than at low frequencies, and the said baffles being arranged to provide successive sound chambers of increasing cross-sectional area from the rear of the loud-speaker to the other opening in the front of the cabinet whereby to reproduce efficiently the low frequency sounds, the last of the said successive sound chambers being of sufficient volume to house a radio receiver chassis and associated elements which reduce the volume of said chamber to cause its effective volume to be in proper relation to the preceding sound chambers.
